UNITED STATES PATENT OFFICE.

FRANZ TRINKS, OF BRUNSWICK, GERMANY.

CALCULATING-MACHINE.

1,118,829.

Specification of Letters Patent.

Patented Nov. 24, 1914.

Application filed May 6, 1914. Serial No. 833,727.

To all whom it may concern:

Be it known that I, FRANZ TRINKS, manufacturer, a citizen of the Duchy of Brunswick, Empire of Germany, residing at 5 Brunswick, Germany, have invented certain new and useful Improvements in Calculating-Machines, of which the following is a specification.

My invention relates to improvements in 10 calculating machines, and more particularly in calculating machines of that class in which two groups of setting members of the setting mechanism are adapted to be temporarily connected by means of a coupling 15 mechanism, so that the value set in one setting mechanism or the number which complements the said value to the next higher power of ten appears in the other group of setting members.

20 A machine of this class and the object of the mechanism have been fully described in the patent of the United States No. 1,075,073 granted to me January 4, 1913. As shown in the said patent the coupling members are 25 provided by gear wheels and shafts which are mounted on a common frame adapted to be rocked about a horizontal axis or to be shifted in the direction of the axis of the gear wheels with the gear wheels into and 30 out of coupling positions. For throwing the gear wheels completely out of coupling position the frame must perform a comparatively large rocking or shifting stroke, so that it requires much room in the machine.

35 The object of the improvements is to construct a coupling mechanism between the groups of setting members which requires less space.

With this object in view my invention consists in so constructing the said mechanism, that each coupling member for connecting two setting members is mounted for radial displacement relatively to the axis of the setting mechanism independently of the other 45 coupling members, and that all the coupling members are adapted to be operated by a common operating member.

For the purpose of explaining the invention two examples embodying the same have 50 been shown in the accompanying drawing, in which—

55 Figure 1, is a vertical cross-section of a calculating machine showing the improved coupling mechanism, and Fig. 2, is a partial vertical cross-section showing a modification of the coupling mechanism.

The general construction of the calculating machine is shown and described in my aforesaid Patent No. 1,075,073, so that a detailed description of the parts is not necessary. 60

In the example shown in Fig. 1, the groups of setting members or cam disks 1 of corresponding orders are adapted to be coupled by means of gear wheels 3 mounted on shafts 65 2. The said shafts 2 are disposed in radial slots 4 of a pair of stationary upright arms 5. For shifting the coupling members operating members or slides 6 are provided which are shiftable on the arms 5. The operating members 6 may be connected with each other, and by shifting the same by means of a push button 7 or the like from the position shown in Fig. 1 downward and in the direction of the arrow x, the coupling 70 members are forced outward by means of oblique slots 8 engaging the shafts 2, so that the coupling members are thrown out of engagement with the teeth 14 of the setting disks 1. By shifting the push button 7 and 75 the slides 6 in the opposite direction the coupling members are moved in radial direction and into engagement with the setting disks 1. Preferably the end positions of the operating slides 6 are indicated to the operator 80 by means of spring actuated pawls 10 engaging in notches 9.

In the example shown in Fig. 2 rocking levers 11 and 12 are provided for throwing the coupling members into and out of operation, which rocking levers are supported on arms 5'. The arms 11 and 12 of the said levers are bifurcated at their ends, and the arms 11 engage the shafts 2' of the coupling members 3 which are adapted to be thrown 95 into and out of cooperation with the teeth 14' of the setting disks 1', and the arms 12 are adapted to be operated by means of curved operating bars 13 engaging with pins in the bifurcated ends of the said arms. As 100 shown the said bar is mounted on pins 15 engaging in slots 16 of the bar and secured to the arms 5' or, as shown, to the side walls 17 of the casing of the machine. Also in this case the arms 5' are provided with radial 105 slots 4' providing sliding supports for the shafts 2' of the coupling members. The slide bar 13 is adapted to be operated by any suitable means such for example as a push button 7', and it is adapted to be locked in 110 its end positions by means of a spring actuated pawl 18.

I claim herein as my invention:

In a calculating machine, the combination with setting members arranged in sets in different portions of the machine, and registering members coöperating therewith, of mechanism to connect corresponding setting members for common operation, the connecting members for each pair being mounted for independent displacement toward and away from the axis of the setting mecha-

nism, and common operating means for all the coupling members.

In testimony whereof I have hereunto set my hand in presence of two subscribing witnesses.

FRANZ TRINKS.
